FOREIGN PATENT DOCUMENTS

CA 23613 10/1960

(Continued)

Primary Examiner — Ricky Pham

(74) Attorney, Agent, or Firm — Banner & Witcoff, Ltd.

(57) **CLAIM**

The ornamental design for a hand mixer handle, as shown and described.

DESCRIPTION

FIG. 1 is a perspective view of a hand mixer handle showing my new design;

FIG. 2 is a left side view thereof;

FIG. 3 is a front view thereof;

FIG. 4 is a right side view thereof;

FIG. 5 is a rear view thereof; and,

FIG. 6 is a top plan view thereof.

The broken line showing of the remainder of the hand mixer handle is for environmental purposes only and forms no part of the claimed design.
